PICKLING TANK STRUCTURE

Julius A. Clauss, Detroit, and Donald E. McGuire, Wyandotte, Mich., assignors to Great Lakes Steel Corporation, Ecorse, Mich., a corporation of Delaware

Application May 17, 1937, Serial No. 143,074

6 Claims. (Cl. 266—7)

This invention relates to pickling tank structures and particularly to pickling tanks of the continuous type wherein a plurality of such tanks are arranged in generally end to end relationship and the steel to be pickled is moved continuously from tank to tank in wire, rod, or strip form, the principal object being to provide a structure of this type in which the corrosive gases will be withdrawn from over the tanks and discharged at a remote point without contaminating the atmosphere of the room or building in which the tanks are situated, and which will resist corrosion or like effects of the pickling solutions and vapors upon the apparatus.

15 Objects of the invention include the provision of a new and novel form of apparatus for withdrawing the vapors tending to arise from pickling tanks and discharging the vapors at a point remote therefrom; the provision of a construction
20 as above described including vapor withdrawal ducts positioned between the ends of a pair of pickling tanks and so constructed and arranged as to effectively cooperate with the tanks and to resist corrosion by the vapors withdrawn therethrough; the provision of means for withdrawing the vapors from a plurality of pickling tanks arranged in end to end relationship including a longitudinal duct arranged below the pickling tank and so constructed as to drain liquid therethrough in one direction and to withdraw vapors or gases therethrough in the opposite direction, in combination with branch ducts extending therefrom intermediate the adjacent ends of adjacent tanks with their upper end portions co-operating with the upper marginal walls of the ends of the tanks so as to withdraw corrosive vapors therefrom; the provision of a construction as above described in which means are provided for variably controlling the volume of
30 gases withdrawn through each of the branch ducts; and the provision of a construction as above described in which the tanks and ducts are formed from sheet metal and provided with a rubber or like coating on all of those surfaces thereof which are liable to come into contact with the corrosive vapors surrounding or being withdrawn from the pickling tanks.

The above being among the objects of the present invention, the same consists in certain novel features of construction and combinations of parts to be hereinafter described with reference to the accompanying drawings, and then claimed, having the above and other objects in view.

In the accompanying drawings which illustrate a suitable embodiment of the present invention

and in which like numerals refer to like parts throughout the several different views,

Figure 1 is a fragmentary, partially broken, vertical sectional view taken centrally and longitudinally through a series of pickling, rinsing and/or like tanks arranged in end to end relationship; 5

Fig. 2 is an enlarged, vertical sectional view taken transversely of one of the tanks shown in Fig. 1 as on the line 2—2 thereof; 10

Fig. 3 is an enlarged vertical sectional view taken transversely through the mechanism shown in Fig. 1 as on the line 3—3 thereof;

Fig. 4 is a fragmentary, vertical sectional view on a slightly smaller scale than Fig. 3 and taken 15 as on the line 4—4 thereof;

Fig. 5 is an enlarged, fragmentary sectional view taken in the same plane as Fig. 3 and showing a modified form of constructions.

Referring to the drawings, the floor of a building or room in which the pickling tanks are situated is indicated at 10 and as being provided with two rows of piers 12 each of which below the corresponding pickling tank supports at its top a longitudinally extending I-beam 14. A plurality of transversely extending I-beams 16 bridge the I-beams 14 and are arranged in relatively closely associated relationship so as to provide a substantially continuous support for a pickling tank indicated generally at 18 resting thereon. As is understood by those skilled in the art where pickling tanks are arranged for the continuous pickling of sheet or strip steel a number of these tanks are arranged in line and in generally spaced relationship and means are provided for drawing the strip stock continuously through the pickling solution which is contained in these tanks. Generally from two to six and usually four such pickling tanks are arranged in series and at their discharge end one or more rinse tanks for rinsing the pickling solution from the strip stock are positioned in line with the pickling tanks. Usually the pickling tanks are in the neighborhood of sixty feet long with an effective depth of from two and one-half to four and one-half feet and of sufficient width to take the widest sheets that it is intended to pass through the tank. Generally these tanks

pass through the tanks. Generally these tanks are spaced from one another at their ends by a distance of two to three feet and suitable rolls or other mechanism are provided above the adjacent ends of adjacent tanks to support and guide the strip stock over the end walls of the tanks, the strip stock sagging between opposite ends of the tanks so as to be immersed in the pickling solution, rinse solution or the like con-

tained within the tanks. In the past it has been common practice to form such tanks of brick work and to seal the interior surfaces thereof against the penetration of the pickling acid solution by means of pitch or other like plastic sealing material. However, because of the length of such tanks brick tanks frequently crack and allow seepage and leakage of the pickling solution out of the tank which not only has a tendency to foster early destruction of the tank and corrode metal parts with which it comes in contact but the fumes arising from such acid solution also acts to corrode any metal parts with which it contacts.

15 It has also been suggested in the past to provide hoods over the tanks and to provide means for exhausting air from the hoods whereby to eliminate to a great extent the presence of the acid fumes from the room or building in which the tanks are located not only to better protect the health of the workmen engaged around the tanks, but also to prevent the corrosive effects of the acid fumes which otherwise would rise from the tanks and come in contact with various metallic parts throughout the building or room in which the tanks are located. The means provided for this purpose in the past, however, have been extremely conspicuous and thus detracted from the appearance of the tanks, they have taken up floor space which could otherwise be employed to advantage and have not been protected to a desirable extent against the corrosive effects of the vapors and pickling solution. The present invention is particularly designed to obviate the above described disadvantages of heretofore employed constructions.

Inasmuch as the rinse tanks employed in series with the pickling tanks are preferably of identically the same construction as the pickling tanks except perhaps in actual length or other dimensions, both the pickling tanks and rinse tanks will hereinafter be referred to as pickling tanks, or simply as tanks, for simplicity of description, it being understood that in the following description certain of the problems discussed will be common to both pickling and rinse tanks, while some may apply only to the pickling tanks.

As indicated in the drawings the various tanks 18 are preferably formed from sheets or plates of metal, preferably steel, suitably reinforced where necessary or desirable, and welded into a unitary structure. In other words, each tank includes a bottom plate 20, side plates 22 and as indicated in Fig. 4 end plates 24. As indicated best in Fig. 2 a downwardly opening channel member 26 is fixed to the outer face of and extends the full length of each side plate 22 with its upper surface in slightly downwardly spaced relation with respect to the upper edge of the corresponding plate 22. A smaller downwardly opening channel member 28 is secured in a corresponding position on the inner face of each side plate 22 and similarly extends the full length of the corresponding side plate 22. The channels 26 and 28 act to stiffen the upper edge of the tank 18 and to prevent spreading thereof, but such spreading may be further guarded against by the provision of buttress members 30 projecting upwardly from the outer end portions of the various cross-channels 16 and in engagement with the outer faces of the side plates 22.

As best indicated in Fig. 4 the end plates 24 of each tank 18 are each provided with a strip 76 or plate 32 of metal across its upper edge and

which plate or strip extends the full length thereof. The plates 32 over-hang both the inner and outer faces of the corresponding end plates and are preferably tilted a slight amount downwardly toward the interior of the corresponding tank 18 as indicated. The joints between each plate 32 and its corresponding end wall 24 may be reinforced if desired by the provision of an angle member such as 34 fitted between the outer face of the corresponding end wall 24 and the under-face of the outwardly projecting edge portion of the plate 32.

The inner surfaces of the bottom 20, sides 22 and ends 24 of each tank 18 are completely lined with a layer 36 of rubber which is suitably vulcanized, adhered, or otherwise secured to or against such surfaces so as to completely mask them. Along the sides as indicated in Fig. 2 the rubber lining 36 is extended inwardly around the channels 28, then upwardly and outwardly over them and then upwardly over the upper edges of the side plate 22 and down on the outside to the upper surface of the corresponding channel 26. At the ends the lining 36 is extended inwardly, then up and over the corresponding plate 32 to the extreme outer edge of the same. The extension of the lining 36 in this manner over the upper edge portion of the sides and ends of the tanks 18 is carried out so as to protect such edges against the action of corrosive vapors from the pickling solution which are liable to escape at such edges in spite of the fact that a large volume of air is withdrawn from the surface of the tanks in order to prevent such escape as will hereinafter be more fully explained.

Additionally, the interior of each tank 18 is further provided with a lining 38 of material impervious or substantially impervious to the effects of the acid in the pickling solution. Ordinarily the lining 38 will be formed of brick work 40 and it is provided for the purpose of preventing abrasion of the rubber lining 36 from the strip material being passed through the pickling solution in the tanks 18. It will thus be understood that each tank 18 is formed from metal and preferably steel and is effectively sealed against the corrosive action of the acid pickling solution by means of the rubber lining 36 and the lining 38 is protected against abrasion or damage by the strip material being treated by means of the lining 38. Accordingly, it is of little importance whether the lining 38 is impervious to the passage of the pickling solution or not.

Each tank 18 is provided with a removable cover indicated generally at 40. Each cover 40 is of partially cylindrical formation positioned with its concave side facing downwardly and its end portions resting upon the upper edges of the lining 38 along the side of the tank. It will be understood that the covers extend substantially the full length of the tanks 18. Each cover 40 is preferably formed from sheets or plates 42 of metal and are reinforced along their marginal side edges by means of suitable angles 44 secured to the outer face thereof along such side edges and preferably by the addition of other longitudinally extending angle members such as 46 secured at intervals over the width of the cover. Additionally, transversely extending angle members such as 48 may be provided on the outer surface of the plates 42 at the ends and at intervals over the length of the cover 40 to further stiffen the construction. A rubber lining 50 completely masks the inner surface of the plates 42 and as indicated in Fig. 2 this rubber lining ex-

tends outwardly over the marginal side edges of the cover 40 in completely embracing relationship with respect to the side angles 44. Accordingly, the same degree of protection against the corrosive action of the pickling solution is afforded the cover 40 by means of its lining 50 as is afforded each tank 18 by its lining 36.

As best illustrated in Fig. 4 the covers 40 terminate a short distance from the corresponding end of the corresponding tank 18 particularly for the reason that rolls such as 56 extending over substantially the full width of the tanks 18 and slightly above the upper edges thereof are provided between each pair of adjacent tanks 18 for the purpose of guiding the strip material which is indicated generally at 58 in Fig. 1, over the end walls of the tanks. Accordingly, a housing indicated generally at 60 is provided to house the rollers 56 and to bridge the adjacent ends of adjacent covers 40. As in the case of the tanks 18 and the covers 40 the housing 60 is formed from metal plates suitably lined on their inner surfaces with rubber. As best indicated in Figs. 3 and 4, each housing comprises side plates 62, and end plates 64 which are suitably apertured for the passage of the strip material 58 therethrough, and a removable top plate 66. The side plates 62 and end plate 64 are provided with an angle member 68 secured to the inner faces thereof around the upper marginal edges thereof, and all members of the housing 60 thus described are provided with a rubber lining 70 extending over all free edges thereof in a manner similar to that described in connection with the covers 40 and tanks 18.

Extending longitudinally and centrally of the series of tanks 18 and suitably supported upon the floor 10 below them is a duct indicated generally at 74. Although this duct may be of any desired cross-sectional configuration, as a matter of illustration it is shown rectangular in section and similarly to the tanks 18 is formed from sheets of metal to provide a bottom wall 76, side walls 78 and top wall 80. The bottom wall 76 and side walls 78 are preferably welded to one another and are provided at their adjacent edges with angles 82 to stiffen the connection between them. The upper edges of the side walls 78 are preferably outwardly flanged as at 84 to provide a seat of ample area for reception of the top wall 80 thereon and which top wall is removably secured thereto in any suitable manner. A rubber lining 86 is provided for the bottom wall 76, and side walls 78 and as indicated in Fig. 2 extends outwardly over and around the flange 84. The top wall 80 is lined on its lower side with a rubber lining 88 which extends outwardly up and over the outer marginal edges thereof as indicated. If desired, as indicated, in Fig. 1 the duct 74 may be of varying or stepped cross-sectional area from one end thereof to the other and the lower wall 86 thereof inclined downwardly toward the smaller end thereof so as to effect drainage of liquid fed thereto towards the small end. Also as indicated in Fig. 1 the duct 74 will usually be made up of a plurality of sections suitably connected together.

The duct 74 is provided for two purposes one of which is for carrying away used pickling solution, rinse water or the like which it is desired to discharge from the tanks 18, and the other of which is to provide a duct for withdrawing air from over the surfaces of the tanks 18 and below the covers 40 thereof so as to prevent the escape of corrosive vapors from the tank 18 and for car-

rying such vapors away to some remote point and there discharging them. In order to discharge the contents of the tanks 18 into the duct 74 the following construction is preferably provided.

Referring now to Fig. 2 a pipe such as 90 is projected through a side wall of a tank 18 and at its inner end is connected with a downwardly extending pipe 92 located closely adjacent a side of the lining 38 and opening into the tank a short distance above the bottom thereof. The outer end of the pipe 90 is connected into an ejector 94 whose discharge side is connected by means of a pipe line 96 with the duct 74. The liquid contents of the tanks 18 thus discharged into the duct 74 will flow by gravity therethrough towards the lefthand end thereof as viewed in Fig. 1 from which they will be discharged into a sewer such as 98 or other suitable point of discharge, collection and/or treatment. The liquid discharge end of the duct 74 is preferably turned downwardly and that portion of the sewer 98 which receives it is so constructed and arranged that such downwardly turned end of the duct 74 projects below the normal level 99 of the liquid in the sewer, so that a liquid seal for such end is provided.

The righthand end of the duct 74 is connected, directly or indirectly, with the intake side of a fan 100 adapted to discharge its contents at a point, for instance such as up a chimney, where the corrosive gas content thereof will produce no injurious effect. In order to withdraw air from the surface of the tanks 18 and deliver them to the duct 74 for passage to the fan 100 the apparatus disclosed in Figs. 3 and 4 is provided. As indicated in these figures, between the adjacent ends of each pair of tanks 18 a somewhat funnel-shaped branch or duct indicated generally at 110 is provided. At its upper end each member 110 is of substantially the same width as the cover 60 positioned thereabove it and at its lower end is preferably of slightly less width than the width of the corresponding portion of the duct 74 into which it is connected. As illustrated in Fig. 4 its thickness is generally less than the distance between the adjacent edges of adjacent plates 32 so as to permit it to be removably inserted between the ends of adjacent tanks 18.

The member 110 is preferably formed from sheet metal or metal plates and is provided with a lining 112 of rubber in the same general manner as the parts heretofore described. In order to receive the lower end of each member 110 the top plate 80 of the duct 74 immediately therebelow is provided with an opening 114 therein and outwardly spaced from the inner margin of such opening is provided with an upstanding collar member 116 integrally secured thereto as by welding. The lining 88 for the cover 80 is extended up over the margins of the opening 114 and upwardly and over the collar 116 so as to substantially mask the same. The lower end of the member 110 is inwardly flanged as at 118 and the lining 112 extended downwardly around the lower edge thereof so as to substantially completely mask such lower edge and so as to provide a rubber to rubber contact between the lower end of each member 110 and the upper face of the cover member 80 and corresponding collar 116 when the lower end of the member is telescopically received therein as shown.

As illustrated in Fig. 4 the front and rear upper marginal edges of the member 110 are outwardly flared and their marginal portions formed to provide an outwardly projecting downwardly opening channel portion 120 and the rubber lining 75

112 is extended so as to completely mask the outer marginal edge portion of the portions 120. The height of the members 110 are preferably such that the members 110 are suspended from the adjacent ends of the tanks 18 through contact of the portions 120 with the outer upper marginal edge portions of the plates 32, thus providing a rubber to rubber contact along these lines of contact. The upper marginal side walls 10 of the members 110, as indicated in Fig. 3, are left plain or unbent and the rubber lining 112 is extended over the same in masking relation as indicated. No seal is required at these points between the sides of the members 110 and the corresponding covers 60 for the reason that a relatively strong suction is present at this area which effectively prevents the escape of corrosive gases at these points.

Accordingly, it will be recognized that the area 20 between the upper faces of the adjacent ends of the tanks 18 is sealed to the corresponding member 110 which discharges directly into the duct 74 so that the suction which is transmitted from the fan 100 to the interior of the various 25 members 110 tends to suck corrosive gases or vapors from both the adjacent tanks 18 and to conduct such gases or vapors to the duct 74.

In order to equalize the suction between the various members 110 it may be desirable, at least 30 in certain instances, to vary the effective cross-sectional area of the discharge end of the members 110. One means of accomplishing this is illustrated in Fig. 3 in which it will be noted that an apertured plate member indicated generally at 130 is shown resting upon the inwardly turned flanges 118 at the bottom of the member 110. This plate member 130 may be constructed of sheet metal and completely encased in a rubber covering 132 in order to protect it from the corrosive effects of the pickling vapors being withdrawn through the member 110. The size of the 40 apertures in the plate members 130 may be varied between the various members 110 in order to modify the effective suction in each member 110 45 and thereby enable the suction over all of such members to be equalized or otherwise controlled.

The same effect may also be obtained by the means illustrated in Fig. 5 in which it will be noted that instead of employing an apertured plate such as 130 in Fig. 3, a damper member 50 140 is provided in the reduced lower end portion of the member 110 and is provided with an operating shaft 142 extending to the exterior of the member 110 and by means of which the rotatable position of the damper 140 may be readily controlled to vary the suction effect within the member 110. It will be understood, of course, that the damper member 140 will preferably be completely encased in rubber in much the same 55 manner as the member 130 just described.

The results of the above described construction is that all parts of the pickling tanks and their co-operating apparatus are formed primarily from steel or other suitable metal that 60 may be readily rendered absolutely leakproof and free from danger of cracking, breaking or the like as occurs in brick pickling tank structures, and also that all surfaces, joints and the like of such sheet metal or metal plates are protected 65 by a covering or lining of rubber impervious to the action of the pickling acid and so arranged as to protect all metallic parts against the corrosive effects of the pickling vapor wherever such vapor is liable to escape. Additionally, the drainage duct 74 for carrying away the waste pickling 70

liquid, as well as for carrying away the corrosive vapors from the surfaces of the pickling tank is located below the pickling tank where it does not restrict the use of otherwise available floor space and in a position where it is not readily observed and the branch ducts 110 are so located as to be effective in operation and substantially hidden from view. The result of the entire construction is that an apparatus of the type described is provided that is simple and effective in 10 operation, relatively free from service troubles, involves the use of a minimum amount of floor space and is slight in appearance.

Formal changes may be made in the specific embodiment of the invention described without 15 departing from the spirit or substance of the broad invention, the scope of which is commensurate with the appended claims.

What is claimed is:

1. In combination, a plurality of pickling tanks 20 arranged in end to end and spaced relation, each of said tanks being formed from metal, a rubber lining for each of said tanks extending in embracing relation with respect to the marginal edges thereof, a conduit extending below said tanks, 25 said conduit being formed from metal, a rubber lining for said conduit, branch conduits extending from the first mentioned conduit upwardly therefrom between the adjacent ends of adjacent said tanks and removably suspended from the 30 upper edge portions of the ends of the said adjacent tanks, said branch conduits being formed from metal, a rubber lining for said branch conduits extending into embracing relationship with respect to the upper ends of said branch conduits, 35 hood means overlying said tanks and said branch ducts, and means for withdrawing air through the first mentioned conduit.

2. In combination with a plurality of pickling tanks arranged in end to end and generally spaced 40 relation with respect to each other, a conduit positioned below said tanks and extending longitudinally thereof, said conduit being inclined whereby liquid introduced thereinto will flow by gravity toward one end thereof, means for discharging the contents of said tanks into said conduit, means including a branch conduit interposed between adjacent ends of said tanks opening into the first mentioned conduit at the lower end thereof and having the upper end operatively 50 associated with the upper marginal portions of co-operating tanks, a rubber lining for said branch conduit, cover means substantially enclosing the tops of said tanks and serving as ducts to conduct vapors from said tanks to the upper 55 ends of said branch conduit, and means operatively connected to that end of the first mentioned conduit opposite that towards which said liquid drains for withdrawing air therefrom.

3. In combination, a plurality of pickling tanks 60 arranged in end to end and generally spaced relation, a conduit positioned below said tanks, and means including a branch conduit located between the adjacent ends of said tanks for conducting vapors from the surfaces of said tanks 65 to the first mentioned conduit, said branch conduit having telescopic engagement with the first mentioned conduit and having an outwardly flared upper end engaging the upper adjacent end surfaces of the tanks and supporting the 70 weight of said branch conduit through said engagement.

4. In combination, a plurality of pickling tanks arranged in end to end and generally spaced relation, a conduit extending longitudinally of 75

5 said tanks therebelow, said conduit having an opening in the upper wall thereof in substantial vertical alignment with the space between adjacent ends of the tanks, an upstanding collar surrounding said opening, a layer of rubber overlying the inner surface of said collar and extending over the free marginal edge thereof, a branch conduit extending from said opening upwardly between the ends of the tanks and opening adjacent the upper edges of said tanks, said branch conduit being formed from sheet metal, a rubber lining for said branch conduit, said rubber lining embracing the free marginal edges of said branch conduit, the lower end of said branch conduit being telescopically received in said collar and the upper end of said branch conduit being supported upon the upper edges of said adjacent ends of the tanks.

10 5. In combination, a plurality of pickling tanks arranged in generally end to end and spaced relationship, a conduit disposed below and extending longitudinally of said tanks, means substantially enclosing the tops of said tanks, means communicating the space above said tanks and below the first mentioned means with said conduit comprising branch conduits operatively connected at their lower end to the first mentioned conduit and extending upwardly therefrom between adjacent ends of adjacent tanks and opening adjacent the upper edges of adjacent tanks, said branch conduits being formed from metal and removably suspended upon said tanks, a rubber lining for each of said branch conduits, and

15 said rubber lining enclosing the upper marginal edge portions of said branch conduits and bearing against the upper marginal portion of the adjacent end walls of corresponding adjacent tanks, and means operatively associated with each of said branch conduits operable to vary the effective cross-sectional area thereof.

20 6. In combination, a plurality of pickling tanks arranged in generally end to end and spaced relationship, a conduit disposed below and extending longitudinally of said tanks, means substantially enclosing the tops of said tanks, means communicating the space above said tanks and below the first mentioned means with said conduit comprising branch conduits operatively connected at their lower end to the first mentioned conduit and extending upwardly therefrom between adjacent ends of adjacent tanks and opening adjacent the upper edges of adjacent tanks, said branch conduits being formed from metal 20 and being removably suspended upon said tanks, a rubber lining for each of said branch conduits, and said rubber lining enclosing the upper marginal edge portions of said conduits and bearing against the upper marginal portion of the adjacent end walls of corresponding adjacent tanks, and means comprising apertured plate members received in said branch conduits and forming orifice members for the flow of fluid there-through. 30
